(57) **CLAIM**

The ornamental design for a booster seat as shown and described.

DESCRIPTION

FIG. 1 is an upper, front perspective view of the booster seat of the present invention showing our new design;

FIG. 2 is a front view thereof;

FIG. 3 is a back view thereof;

FIG. 4 is a first-side view thereof;

FIG. 5 is a second-side view thereof, the second-side view being opposite the first-side view;

FIG. 6 is top view thereof; and,

FIG. 7 is a bottom view thereof.

The portions shown in broken lines do not form any part of the claimed design.
